DAVID D. RULLMAN,

Abb. Janissen.

By David O. Barnell.
Attorney.

UNITED STATES PATENT OFFICE.

DAVID D. RULLMAN, OF OMAHA, NEBRASKA.

OPERATING DEVICE FOR WASHING-MACHINES.

1,335,754.

Specification of Letters Patent.

Patented Apr. 6, 1920.

Application filed January 18, 1918. Serial No. 212,800.

To all whom it may concern:

Be it known that I, DAVID D. RULLMAN, a citizen of the United States, and a resident of Omaha, in the county of Douglas 5 and State of Nebraska, have invented certain new and useful Improvements in Operating Devices for Washing - Machines, of which the following is a specification.

My invention relates to washing machines 10 of the type employing a reciprocating dasher or pounder, and more particularly to driving or actuating mechanism for such machines. It is the object of my invention to provide a compact, efficient and durable mechanism for imparting to the dasher a reciprocating movement combined with an alternating rotary movement. A further object of my invention is to provide a driving mechanism which may be 20 actuated either by belt-power, as where a suitable motor is available, or by hand, the movement received from the latter being oscillatory. A further object of my invention is to provide for the hand-driven mechanism a handle which may be placed in different positions to relieve fatigue of the operator, and to provide for the mechanism a high-speed fly-wheel for steadyng the reciprocating or oscillatory motion. A further object of my invention is to provide in a mechanism of this class a single main drive-gear toothed internally and externally, and imparting motion at different ratios to pinions 30 engaging the internal and external gear-teeth.

In the accompanying drawings Figure 1 is a side elevation of mechanism embodying my invention, Fig. 2 is a vertical section thereof on the plane of the line 2—2 40 of Fig. 3, Fig. 3 is a plan view of the mechanism, Fig. 4 is a vertical section substantially on the plane of the line 4—4 of Fig. 3, and Fig. 5 is a detail vertical section through the dasher.

There is shown in the drawings a portion 45 only of the main body of the washing machine, which includes a suitable tub or water receptacle 6, a frame 7, and a top or cover 8 attached to the frame by hinges 9 and 10. The actuating mechanism, with the exception of the fulcrum-bracket for the hand-lever, is carried entirely by the hinged cover, so as to swing up therewith when the cover is raised to open the tub.

The cover-attached portion of the hinge 50 10 is integral with the base-plate 11 of the

actuating mechanism. Said base-plate is secured to the cover by screws 12, and has a portion 13 extending laterally to the outer edge of the frame 7, said portion 13 forming a bearing for a horizontal shaft 14. A fly-wheel 15 is carried on the outer end of said shaft, and on the inner end thereof is a pinion 16 which meshes with the external teeth 17 of the main drive-gear. Said drive-gear comprises an annular rim having the teeth 17 on its outer side and gear-teeth 18 formed on the inner side thereof, the rim being carried by a dished web-portion 19 joining one side thereof, and the web-portion having a central laterally extending hub 20. From the base-plate 11 a standard 21 extends up adjacent to the open side of the main gear, and from the upper end of said standard an arm 22 extends first 25 laterally through the opening within the annular rim and then horizontally adjacent to the vertical part of the dished web-portion 19. On said arm 22 there is carried a fixed stud which extends horizontally 30 through the hub 20 to revolvably support the main gear, and on the opposite side of the arm there is a stud 23 on which a pinion 24 is revolvably mounted. Said pinion 24 meshes with the internal gear-teeth 18, the 35 pinion being eccentric to the gear and in full mesh therewith at a point diametrically opposite the laterally extending portion of the arm 22. On the pinion 24 there is carried a crank-pin 25, with which is 40 pivotally connected the lower end of a bar 26 forming part of a yieldable connecting-member between the pinion and the dasher-shaft 27. The dasher-shaft is preferably 45 tubular and extends vertically, being held 50 slidably and rotatably in suitable bearings formed at the upper and lower ends of a shell 28 secured to the cover 8 over an opening near the center thereof. The intermediate portion of the shell 28 is semi-cylindrical in form, and on the inner side thereof are two helically extending ribs 29 which form between them a trackway for a roller 30 carried by an arm 31 secured on the intermediate portion of the dasher-shaft. 55 The hub-portion of said arm 30 is forked and receives, between the upper and lower parts of the same, the annular horizontal lower end-portion of a yoke 32. The body 60 of said yoke extends vertically, and near its upper end there is a second annular horizontal portion which fits around the upper 65 70 75 80 85 90 95 100 105 110

end-portion of the dasher-shaft. At the upper end of the yoke there is a laterally extending stud 33 with which the head of a rod 34 is pivotally connected. Adjoining the head thereof, said rod 34 is square and extends slidably through a square opening in the head of the bar 26, while the cylindrical lower portion of the rod passes slidably through a lug 35 on the lower portion of said bar 26. A coil spring 36 is disposed around the intermediate portion of the rod 34, the upper end of said spring engaging the head of the bar 26, and the lower end of the spring engaging a cross-pin 37 which extends through the rod adjoining the lug 35. The bar 26, rod 34 and spring 36 form together a yieldable connecting-rod between the crank-pin 25 and the yoke 32, said connecting-rod being capable of elongation by compression of said spring 36 as the cross-pin 37 is moved up toward the head of the bar 26. By means of said connecting-rod, rotation of the crank-pinion 24 causes a vertical reciprocating movement of the yoke 32, which is communicated to the dasher-shaft, and during such movement of the shaft the arm 31 is guided by the roller 30 in the helical trackway between the ribs 29, so as to cause an alternating rotational movement of the shaft, in addition to or combined with the reciprocating motion thereof.

At one side of the frame a bracket 38 is secured thereto, and to said bracket is pivotally connected a lever 39 having in the upper part thereof two sockets, each adapted to receive the end of a handle 40, so that said handle may extend from the lever in either of the two positions shown by full and dotted lines in Fig. 1. From said lever 39 a pitman 41 extends to a crank-pin 42 on the web-portion 19 of the main drive-gear, said pitman having a bowed intermediate portion 43, to enable it to pass the hub 20 during rotation of the gear. By oscillation of the hand-lever 39, imparted thereto by moving the handle 40 back and forth, the main gear is driven therefrom through the medium of the pitman 41. When starting the movement, should the crank-pin 42 be on a dead-center, the fly-wheel 15 may be turned slightly to drive the gear through the medium of the shaft 14 and pinion 16, and after the fly-wheel is in motion its momentum serves to steady the motion of the gear and to drive the same during the times when the crank-pin is near its dead-centers. It will be noted, of course, that owing to the small size of the pinion 16, the rate of rotation of the fly-wheel is quite rapid proportionally to the rate of rotation of the main gear, so that the momentum of the fly-wheel will be very effective in producing uniformity of rotation of the gear. Where a suitable motor is available, the same may be con-

nected by belt with the fly-wheel and the mechanism driven therefrom, in which case the pitman 41 is preferably disconnected from the crank-pin 42.

The teeth 17 of the main drive-gear are 70 guarded by a U-shaped shield 44, of which the ends are connected with the cover 8 and base-plate 11, as shown. The lower end of the shaft 27 is provided with a suitable dasher, of which the preferred construction 75 is indicated in Figs. 4 and 5. The dasher is of the so-called "vacuum" type, and comprises a conical sheet-metal member 45 provided externally with a plurality of semi-conical projecting parts 46, open at their 80 lower ends, the member 45 also having on the inside thereof near its upper end a perforate horizontal diaphragm 47, as shown in Fig. 5. The dasher is secured to the threaded lower end of the tubular shaft 27 by means of 85 two nuts 48 and 49, the latter fitting within the apex of the member 45 above the perforate diaphragm 47, and the nut 48 being screwed on the shaft above the dasher, as shown. The nut 49 has a cylindrical portion 90 extending below the end of the shaft and inclosing a valve-disk 50 which controls the admission and escape of air through the shaft to and from the inside of the conical member 45. Openings 51 are provided in 95 the sides of the member 45 beneath each of the projecting parts 46.

In the operation of the machine, should there be an excessive amount of material beneath the dasher during the downward 100 stroke thereof, excessive stresses upon the driving mechanism are prevented by elongation of the yieldable connecting-rod between the yoke 32 and crank-pin 25, as before described. The disposal of the pinion 24 within the annular drive-gear, provides a very compact arrangement of the mechanism, and avoids the use of extra shielding or guarding means for the gearing. The provision of the two sockets for the handle 40, by permitting the handle to extend either diagonally or approximately vertical, enables the operator to avoid fatigue by occasionally changing the position and thus altering the direction of pressures required to move the 105 handle. The high-speed fly-wheel facilitates the driving of the mechanism by compelling a smooth and uniform movement of the rotary parts. The combined reciprocating and rotary movements of the dasher cause a 110 maximum agitation of the materials engaged thereby, so that the machine has the advantages of both the simple reciprocating dasher type and of the rotating or dolly type of washing machines. When opening the 115 tub, by swinging the cover 8 up about the hinge-axis thereof, the hand-lever swings out from the machine far enough to accommodate the altered location of the crank-pin 42, so that it is unnecessary to disconnect 120 125 130

the pitman 41 or any part of the drive mechanism.

Now, having described my invention, what I claim and desire to secure by Letters Patent is:

1. In a washing machine having a reciprocating dasher-shaft, actuating means for said dasher-shaft comprising an annular gear having a dished web-portion, a pinion disposed within said gear and meshing therewith, a supporting arm extending between said pinion and the web-portion of the annular gear and carrying studs on which the gear and pinion are revolute, a crank-pin on said pinion, means connecting said crank-pin with the dasher-shaft, and means for actuating said annular gear.

2. In a mechanism of the class described, a horizontal arm having a laterally offset portion connected with a support, studs extending from opposite sides of said arm, an annular gear having a dished web-portion revolvably mounted on one of said studs, a pinion revolvably mounted on the other stud, the gear extending around the arm and meshing with the pinion at a point diametrically opposite the offset portion of the arm, crank-pins carried on opposite sides of the gear and pinion, and pitmen connected with said crank-pins and adapted to drive and be driven thereby respectively.

3. In a mechanism of the class described, an arm having a laterally offset portion connected with a support, studs extending laterally from opposite sides of said arm, a pinion revolvably mounted on one of said studs, an annular gear having internal teeth meshing with said pinion, a dished web carrying said annular gear and revolvably mounted on the other stud, a pitman connected with said annular gear for ac-

tuating the same, a second pinion meshing with ~~teeth~~ formed externally upon the annular gear, and a fly-wheel driven by said second pinion.

4. In a mechanism of the class described, a vertically extending dasher-shaft, bearings in which said shaft is held slidably and rotatably, helical guiding means for causing rotary movement of said shaft simultaneously with longitudinal movement thereof, a yoke having portions in which the shaft fits revolvably; means connecting said yoke and shaft in fixed longitudinal relation, a rotary actuating member having a crank-pin, and a pitman connecting said crank-pin and yoke, said pitman comprising slidably connected parts and resilient means yieldable under tension between the ends of the pitman to enable elongation thereof.

5. In a mechanism of the class described, a reciprocatably and rotatably mounted shaft, a member mounted on said shaft and rotatable relatively thereto, a pitman connected with said member, a revolvably mounted pinion connected with said pitman for actuating the same, an annular gear having internal teeth meshing with said pinion, a dished web carrying said annular gear, a fixed member extending between said pinion and dished web and revolvably supporting the same, said dished web having a crank-pin thereon at the side opposite said pinion, a pitman connected with said crank-pin, an oscillatable hand-lever connected with said last-named pitman for actuating the same, a pinion meshing with external teeth on said annular gear, and a fly-wheel driven by said last-named pinion.

D. D. RULLMAN.
